(57) **CLAIM**

The ornamental design for a combination ceiling fan and light fixture, as shown and described.

DESCRIPTION

FIG. 1 is a perspective view of a combination ceiling fan and light fixture in accordance with my design;

FIG. 2 is a top plan view thereof;

FIG. 3 is a bottom plan view thereof;

FIG. 4 is a front elevation view thereof;

FIG. 5 is a rear elevation view thereof;

FIG. 6 is a left-side elevation view thereof; and,

FIG. 7 is a right-side elevation view thereof.

The closely spaced annular lines on the interior wall of the light fixture shown in FIG. 1 and FIG. 3 are surface ornamentation. The lighter and closely spaced lines in the drawings are surface shading and are not surface ornamentation.

The broken lines in the drawings illustrate portions of the ceiling fan that form no part of the claimed design.
